UNITED STATES PATENT OFFICE

162,762

HANDLE FOR COOKING UTENSILS

Franz Wagner, Chicago, Ill., assignor to Ekco Products Company, Chicago, Ill., a corporation of Illinois

Application January 8, 1949, Serial No. 124

Term of patent 7 years

(Cl. D44—29)

To all whom it may concern:

Be it known that I, Franz Wagner, a citizen of the United States, residing at Chicago, county of Cook, State of Illinois, have invented a new, original, and ornamental Design for a Handle for Cooking Utensils, of which the following is a specification, reference being had to the accompanying drawing, forming part thereof.

Fig. 1 is a top plan view of a handle for cooking utensils, showing my new design.

Fig. 2 is a front elevational view thereof.

Fig. 3 is a side elevational view, and

Fig. 4 is a bottom plan view.

I claim:

The ornamental design for a handle for cooking utensils, as shown.

FRANZ WAGNER.
